[57] CLAIM

The ornamental design for a display object for a display screen, as shown and described.

DESCRIPTION

FIG. 1 is a face view of a display object for a display screen. The broken line drawing of the display screen is for illustrative purposes only and forms no part of the claimed design;

FIG. 2 is a face view thereof, on an enlarged scale, the display is shown separately for clarity of illustration;

FIG. 3 is a face view of a second embodiment thereof, on an enlarged scale, the display object is shown separately for clarity of illustration; and,

FIG. 4 is a face view of a third embodiment thereof, on an enlarged scale, the display object is shown separately for clarity of illustration.
